207,561

COMBINATION VENT AND AIR INTAKE TERMINAL

Karl L. Bedell, Pasadena, Calif., assignor to Williams Furnace Co., Buena Park, Calif., a corporation of Delaware

Filed Nov. 1, 1965, Ser. No. 87,972

Term of patent 14 years

(Cl. D62—3)

FIG. 1.

FIG. 3.

FIG. 2.

FIG. 1 is a perspective view of one embodiment of the combination vent and air intake terminal design, illustrating primarily the front, top and right side of the terminal;

FIG. 2 is a perspective view of the embodiment of FIG. 1, illustrating primarily the front and left side of the terminal;

FIG. 3 is a rear elevation view of the embodiment of FIG. 1;

FIG. 4 is a perspective view of another embodiment of the combination vent and air intake terminal design, illustrating primarily the front, top, and right side of the terminal;

FIG. 5 is a perspective view of the embodiment of FIG. 4, illustrating primarily the front and left side of the terminal;

FIG. 6 is a rear elevation view of the embodiment of FIG. 4.

The design is symmetrical so that the appearance of the combination vent and air intake terminal is the same whether viewed from the top, bottom, or either side.

The dominant features of the design reside in the portions shown in full lines.

I claim:

The ornamental design for a combination vent and air intake terminal, substantially as shown and described.
